UNITED STATES PATENT OFFICE.

THOMAS E. DAY, OF BELLEVILLE, NEW JERSEY, ASSIGNOR, BY MESNE ASSIGNMENTS,
TO HIBBARD PROCESS CORPORATION, OF NEW YORK, N. Y., A CORPORATION OF
NEW JERSEY.

SQUEEZER.

Application filed June 21, 1921. Serial No. 479,128.

To all whom it may concern:

Be it known that I, THOMAS EDWARD DAY, a subject of the King of Great Britain, residing in Belleville, in the county of Essex and State of New Jersey, have invented certain new and useful Improvements in Squeezers, of which the following is a specification.

My present invention relates to squeezers such as are commonly used to squeeze or 10 work masses of puddled iron to remove the slag and to consolidate the mass.

In certain types of puddling furnaces, the puddled iron ball is very much larger than it is when made in the generally used puddling furnace known as the hand furnace, and it also often takes a relatively longer form, somewhat cylindrical in shape. The squeezers ordinarily used for balls of puddled iron cannot be conveniently used when 15 the product is greater in weight, say, above two hundred pounds, and when the form it takes is peculiar in shape as aforesaid.

One of the objects of my invention is to devise a squeezer which will handle masses 25 of puddled iron of the character described, so that the same may be done quickly and certainly in an operation where the loss of a few seconds of time will seriously affect the subsequent operations.

With this and other objects in view, my 30 invention consists in the constructions and arrangements hereinafter described, and more specifically pointed out in the appended claims.

In the drawings, Figure 1 is a central sectional elevation of an illustrative embodiment of my invention; Fig. 2 is a plan of the machine shown in Fig. 1; Fig. 3 is a central vertical section of Fig. 1 with some of the 35 parts omitted and broken away, and Fig. 4 is a detail showing a modification.

The same reference characters refer to the same parts in the several views.

In the illustrative form of my invention, a scroll is formed of a plurality of bed pieces 45 14, each having its ends resting on lips 12 and 13 of a pair of side members 10 and 11. The edges of each piece may be slightly recessed between the lips to form spaces 15, as shown in Fig. 3, through which the slag 50 may flow. If desired, additional openings 16 may be provided through the bed pieces for the same purpose. The surfaces of the bed pieces may be corrugated or roughened, 55 in the usual manner.

In the side members 10 and 11 are journaled the bearings of a roll 17, this roll being positioned so that a channel is formed between the scroll and the surface of the roll, with one end of the channel wider than 60 the opposite end, as is usual in squeezers. The surface of the roll may also be corrugated in the usual manner, and may also be provided with larger projections or dogs, if desired. The roll 17 may be rotated in any 65 convenient manner, as by the gears 18, 19 attached to the shaft of the roll. The means for driving these gears is not shown, but it will be understood that they may be driven in any suitable manner. 70

It is necessary that the cylindrical mass of puddled iron shall be fed through the channel at its wide end, so that the axis of the mass will be approximately parallel to the axis of the roll 17. It is also necessary that this soft, spongy mass shall not be permitted to fall or drop suddenly into the channel, in order to prevent its being wedged into the space before the roll 17 has had an opportunity to begin to rotate 80 and squeeze the mass. I, therefore, provide means by which the mass may be guided and lowered slowly, and preferably at a regulated speed, into the channel. 75

As one convenient arrangement to accomplish this purpose, I have provided a tilting table 20, pivoted on a shaft 21, and preferably supported on a part of the frame of the machine. The table 20 is normally positioned, as shown in Fig. 1, with its inner 85 end extending across the wide end of the channel and sloping downward toward the roll 17. In order to hold the table 20 in this position while sustaining the weight of the puddled mass, I provide a holding device, such as a latch 22 engaging a toe 23 on the table 20. The shaft 21, in the illustrative form, is provided at each end with a sheave 24, over which passes a cable 25, to which is attached a weight 26. Preferably this weight is made up of a number of pieces, so that its weight may be adjusted to suit the operating conditions. 90

The frame of the machine is cut away, as at 27, so that the table 20 may be swung 100 clockwise with the shaft 21 until the table 20 lies within the space 27, out of the channel. 105

As a guiding means for the mass, I have illustrated a pair of guides 28, 29, pivoted 110

at 30, 31, respectively, with the opposite ends of the guides held in adjusted position by bolts 321.

With the parts in the position shown in Fig. 1, the cylindrical mass is dropped on the table 20, down which it moves until it rests against the roll 17, being guided by the guides 28, 29, so that it will not overlie the side members 10 and 11, or, in other words, will be in contact only with the surface of the roll 17. The latch 22 is then tripped and the weight of the mass causes the table 20 to swing downward, but the speed at which it moves will be regulated by the lifting of the weights 26. This will permit the mass to move slowly down into the channel, the table 20 swinging into the space 27 to permit it to pass. The mass will then be gripped between the scroll and the roll 17 and will be squeezed, in the usual manner, as it passes through the channel. The slag squeezed out will pass out through the openings 15 and 16.

When the compacted mass has reached the right-hand, or narrow, end of the channel, its further progress will be stopped when the end of the channel is reached, and in order to remove the mass from the squeezer, I preferably provide a dog 32, pivoted at 33, and preferably supported on the frame of the machine, the dog preferably extending across the space between the side members 10 and 11.

Preferably the dog 32 is weighted, so that it normally lies in the full-line position shown in Fig. 1. The inner face 34 of the dog 32 is preferably formed so that when the dog has swung to the dotted-line position in Fig. 1, the face 34 will constitute a continuation of the channel face of the scroll. When the dog is in the dotted-line position, a toe 35 will contact with some part, such as the top of the frame of the machine, so that it cannot be rotated any further on the pivot 33.

With the parts shown in full-line position in Fig. 1, the squeezed mass will be forced up until it contacts with the face 34 of the dog 32, which will then be rotated to the dotted-line position of Fig. 1, and, by reason of the continued pressure on the mass, it will be forced up until it passes the upper end of the dog. The dog will then swing downward on its pivot 33 until it is again in the full-line position in Fig. 1, and when in this position, the top or upper side of the dog will constitute a kind of platform, down which the finished mass may roll or be otherwise moved out of the machine.

If desired, instead of using the dog 32, I may use the arrangement shown in Fig. 4, in which a series of slots 40 are provided across the frame of the machine, so that a bar 41 may be inserted beneath the mass as it reaches the narrow end of the scroll and

be used to force it out of the squeezer, to be removed therefrom.

In order to prevent the finished mass from being forced over the top of the roll 17, I provide a stop 42.

It will be understood that the arrangement which I have shown is merely illustrative, and that the construction and arrangement may be widely varied.

I claim:

1. In a squeezer, a roll with its axis horizontal, a scroll surrounding the lower part of the roll and spaced therefrom to form a channel progressively decreasing in width from one side of the roll to the other, and means whereby a mass of puddled iron may be lowered slowly into the wide end of said channel while the roll is rotating.

2. In a squeezer, a roll with its axis horizontal, a scroll surrounding the lower part of the roll and spaced therefrom to form a channel progressively decreasing in width from one side of the roll to the other, and means whereby an approximately cylindrical mass of puddled iron may be lowered into the wide end of said channel with the axis of the mass approximately parallel to the axis of the roll.

3. In a squeezer, a roll with its axis horizontal, a scroll surrounding the lower part of the roll and spaced therefrom to form a channel progressively decreasing in width from one side of the roll to the other, and means whereby a mass of puddled iron may be lowered at regulated speed into the wide end of said channel while the roll is rotating.

4. In a squeezer, a roll with its axis horizontal, a scroll surrounding the lower part of the roll and spaced therefrom to form a channel progressively decreasing in width from one side of the roll to the other, and means whereby an approximately cylindrical mass of puddled iron may be lowered at regulated speed into the wide end of said channel with the axis of the mass approximately parallel to the axis of the roll.

5. In a squeezer, a roll with its axis horizontal, a scroll surrounding the lower part of the roll and spaced therefrom to form a channel progressively decreasing in width from one side of the roll to the other, and a tilting table adjacent the wide end of said channel arranged to receive a mass of puddled iron and lower it at regulated speed in said wide end.

6. In a squeezer, a roll with its axis horizontal, a scroll surrounding the lower part of the roll and spaced therefrom to form a channel progressively decreasing in width from one side of the roll to the other, a tilting table adjacent the wide end of said channel arranged to receive a mass of puddled iron and lower it at regulated speed in said wide end, and guides on said table

to locate said mass endwise as it is lowered.

7. In a squeezer, a roll with its axis horizontal, a scroll surrounding the lower part of the roll and spaced therefrom to form a channel progressively decreasing in width from one side of the roll to the other, a tilting table adjacent the wide end of said channel arranged to receive a mass of puddled iron, and means to regulate the speed 10 of the tipping of the table by said mass.

8. In a squeezer, a roll with its axis horizontal, a scroll surrounding the lower part of the roll and spaced therefrom to form a channel progressively decreasing in width 15 from one side of the roll to the other, a tilting table adjacent the wide end of said channel arranged to receive a mass of puddled iron, a latch to prevent said mass from tipping the table, and means to regulate the 20 speed of the tipping of the table by said mass after the latch is released.

9. In a squeezer, a roll with its axis horizontal, a scroll surrounding the lower part of the roll and spaced therefrom to form a channel progressively decreasing in width 25 from one side of the roll to the other, a tilting table arranged to receive a mass of puddled iron and having one end projecting over the wide end of said channel and, when 30 in normal position, with its surface inclined toward said channel, a latch to hold said table in normal position, and means to regulate the speed of the tipping of the table by said mass after the latch is released, 35 the end of the table being arranged to swing out of said channel as the mass passes between the roll and the bed.

10. In a squeezer, a roll with its axis horizontal, a scroll surrounding the lower part 40 of the roll and spaced therefrom to form a channel progressively decreasing in width from one side of the roll to the other, a tilting table arranged to receive a mass of puddled iron and having one end projecting 45 over the wide end of said channel and, when in normal position, with its surface inclined toward said channel, and means to regulate the speed of the tipping of the table by said mass, the end of the table being ar- 50 ranged to swing out of said channel as the mass passes between the roll and the bed.

11. In a squeezer, a roll with its axis horizontal, a scroll surrounding the lower part of the roll and spaced therefrom to form 55 a channel progressively decreasing in width from one side of the roll to the other, a tilting table arranged to receive a mass of puddled iron and having one end projecting over the wide end of said channel and, 60 when in normal position, with its surface inclined toward said channel, and means to regulate the speed of the tipping of the table by said mass, the end of the table being arranged to swing out of said channel 65 as the mass passes between the roll and the

bed, the surface of said table being provided with guides to locate said mass endwise thereon.

12. In a squeezer, a roll with its axis horizontal, a scroll surrounding the lower part 70 of the roll and spaced therefrom to form a channel progressively decreasing in width from one side of the roll to the other, and a pivoted dog adjacent the narrow end of the channel and arranged to permit a mass 75 of squeezed and puddled iron to pass out of said narrow end and to prevent the return of said mass into said channel.

13. In a squeezer, a roll with its axis horizontal, a scroll surrounding the lower 80 part of the roll and spaced therefrom to form a channel progressively decreasing in width from one side of the roll to the other, and a pivoted dog adjacent the narrow end of the channel and arranged to 85 permit a mass of squeezed and puddled iron to pass out of said narrow end and to prevent the return of said mass into said channel, the face of said dog being arranged to form a continuation of said channel when 90 forced to its outer position by a mass of squeezed iron passing through said channel and the body of the dog extending across said channel after the mass has passed the dog. 95

14. In a squeezer, a roll with its axis horizontal, a scroll surrounding the lower part of the roll and spaced therefrom to form a channel progressively decreasing in width from one side of the roll to the other, and a pivoted dog adjacent the narrow end of the channel and arranged to permit a mass of squeezed and puddled iron to pass out of said narrow end and to prevent the return of said mass into said channel, the 100 face of said dog being arranged to form a continuation of said channel when forced to its outer position by a mass of squeezed iron passing through said channel and the body of the dog extending across said channel after the mass has passed the dog, the back of the dog forming an inclined pathway down which said mass may move out of the squeezer. 110

15. In a squeezer, a roll with its axis horizontal, a scroll surrounding the lower part of the roll and spaced therefrom to form a channel progressively decreasing in width from one side of the roll to the other, said scroll comprising a pair of side members and a plurality of separate bed pieces extending between the side members with the ends of the pieces resting on said members, the connections between the pieces and the side members being arranged to permit the pieces to be adjusted toward the roll. 115

16. In a squeezer, a roll with its axis horizontal, a scroll surrounding the lower part of the roll and spaced therefrom to form a channel progressively decreasing in 120 125 130

width from one side of the roll to the other, said scroll comprising a pair of side members each having a lip formed approximately concentric with the outer wall of 5 the channel, and a plurality of separate bed pieces extending between the members with their ends resting on said lips, said lips and said pieces being connected so that the pieces may be adjusted toward the roll by 10 the insertion of distance pieces between the lips and the ends of the pieces.

17. In a squeezer, a roll with its axis horizontal, a scroll surrounding the lower part of the roll and spaced therefrom to form 15 a channel progressively decreasing in width from one side of the roll to the other, said scroll comprising a pair of side members and a plurality of separate bed pieces ex-

tending between the end members with the ends of the pieces resting on said members, 20 said bed being provided with openings between the pieces for the passage of slag.

18. In a squeezer, a roll with its axis horizontal, a scroll surrounding the lower part of the roll and spaced therefrom to 25 form a channel progressively decreasing in width from one side of the roll to the other, said scroll comprising a pair of side members and a plurality of separate bed pieces 30 extending between the end members with the ends of the pieces resting on said members, said bed being provided with openings between and through the pieces for the passage of slag.

THOMAS E. DAY.
